UNITED STATES PATENT OFFICE

JULIAN L. PERKINS, OF WEST SPRINGFIELD, AND HIRAM D. CROFT, OF SPRINGFIELD, MASSACHUSETTS, ASSIGNORS TO PERKINS MACHINE AND GEAR COMPANY, OF SPRINGFIELD, MASSACHUSETTS, A CORPORATION OF MASSACHUSETTS

WORKHOLDER

Application filed March 11, 1927. Serial No. 174,477.

Our invention relates to improvements in mechanisms attachable to or forming parts of broaching machines, and more especially broaching machines of the reciprocating ram type, such as that which constitutes the subject matter of Letters Patent of the United States, issued September 13, 1927, No. 1,642,593, and said invention comprises automatically-operated, yielding or spring-pressed means and mechanism whereby the work is clamped in place and moved into operative position relative to the broaches of the machine, with which this work holder is incorporated, when said broaches in ascending approach or arrive at the upper end of their travel, and moved into inoperative position and unclamped, when said broaches in descending approach or arrive at the end of their downward travel, a safety device to prevent the action of the parts which move the work-carrying members into broaching position, in the event the work be not properly or fully seated in the holder, and mechanism for automatically withdrawing the work from the holder after the latter has been returned to initial or loading position at the end of the broaching operation, all peculiarly constructed and combined, together with such other parts and members as may be necessary and desirable in order to render the work holder complete and serviceable in every respect, all as hereinafter set forth.

One object of our invention is to provide a broaching machine, of the type mentioned above, with means for clamping and carrying the work into the paths of the broaches and out of such paths, holding said work rigidly and securely in place during the movement of the same into and out of said paths and while said work is being acted on by said broaches, and releasing the work when the same is moved out of said paths, all being done automatically except that the cycle of operation of the holder is started by hand. The aforesaid means are comparatively simple, both in construction and operation, yet strong, durable, and not liable to get out of order.

Another object is to afford means, in connection with the manually-operated starting

mechanism, to prevent the operation of said mechanism to the extent necessary to start the cycle of the work holder, in the event the piece of work in the holder is not fully seated therein, whereby are avoided the injury and breakage that would be liable to occur if the work holder were thrown over into broaching position with said piece improperly placed.

A further object is to furnish, in connection with the work holder, an extractor for the work, whereby the same after being broached is automatically removed from said holder.

Other objects and advantages will appear in the course of the following description.

We attain the objects and secure the advantages of our invention by the means and mechanism illustrated in the accompanying drawings, in which—

Figure 1 is a top plan of a work holder which embodies a practical form of our invention, and of a broaching machine, such as that hereinbefore referred to, or the portion of said machine with which said holder is most intimately associated, parts being in section and broken away; Fig. 2, a vertical section through the parts and members shown in the preceding view, taken on lines 2—2, locking in the direction of the associated arrow, in said view; Fig. 3, an outer or left-hand side elevation of the tension or locking device for the rock shaft of the holder; Fig. 4, a detail in cross section of the cam and associated parts and members; Fig. 5, a side elevation of a hinge leaf such as is adapted to be held by the holder and broached by the machine as here presented; Fig. 6, an edge view of said leaf; Fig. 7, a front elevation of the work holder and broaching-machine elements, with parts in section and broken away; Fig. 8, a detail, in partial section, of the work-holding parts and members, and of the safety device; Fig. 9, a detail of the clamp and equalizer; Fig. 10, a right-hand side elevation of the work holder and machine elements; Fig. 11, a fragmentary detail of the lower part of the ram, showing the lower dog secured thereto; Fig. 12, a rear elevation of certain of the work-holding members; Fig. 13, a top plan of the extractor showing the

same supported from the ram; Fig. 14, a front elevation, with parts in section and broken away, of the work-engaging members of said extractor; Fig. 15, a right-hand side elevation, generally similar to Fig. 10, but showing the parts and members differently disposed; Fig. 16, a top plan of actuating mechanism for the ram, and, Fig. 17, a side elevation of the reversing elements of said mechanism.

Similar reference characters designate similar parts throughout the several views.

We will first describe briefly the construction and operation of the parts and members 15 of the broaching machine (apart from the work holder) illustrated in connection here- with.

Mounted to reciprocate vertically on a column 1 is a ram 3, and secured to the front side 20 of said ram is a holder 4 for a central broach 5 and two side broaches 6. The ram 3 is re- ciprocated by means of a rack 7 on one side thereof, and an intermeshing pinion 8 suit- ably mounted in or supported from a bed 9, 25 and driven from any suitable motor or by any motive power controlled to cause said pinion to be reversed each time said ram arrives at either end of its travel, and thus to reverse the direction of movement on the part 30 of the ram. Secured to the side of the ram 3, opposite to that whereon is located the rack 7, are upper and under dogs 10 and 11, re- spectively, arranged to impart to a movable member in their paths movement in opposite 35 directions, as said ram reciprocates.

A shelf 12 has its ends attached to the right- hand side of the bed 9, and between said ends said shelf is spaced from said bed. Mounted on the top of the bed 9 and on the shelf 12, 40 respectively, are bearings 13 and 14 for a rock shaft 15. An arm 16 is rigidly attached to the shaft 15, and extends downwardly be- tween the bed 9 and the shelf 12. The hub of the arm 16 is located on the shaft 15 be- 45 tween the bearings 13 and 14, and an arm 17 is rigidly attached to said shaft between the bearing 13 and the ram 3, and extends up- wardly. At the upper end of the arm 17 is a roll 18, which is located by said arm in the 50 paths of travel of the dogs 10 and 11.

When the ram 3 descends, the dog 10, as it approaches the lower end of its travel, en- counters the roll 18 and actuates it forwardly, thus rocking the arm 17 on the shaft 15 in the 55 same direction, and the arm 16 on said shaft in the opposite direction or rearwardly, into the position shown in Fig. 15; and, when said ram ascends, the dog 11, as it approaches the upper end of its travel, encounters said 60 roll and actuates it rearwardly, thus rocking said first-named arm in the same direction, and said second-named arm forwardly, into the position shown in Fig. 10.

Also included with the old structure are a 65 lever 19, a trip 20 for said lever, a rocker

arm 21 mounted on a stud 22, a hooked link 23, and dogs 24 and 25. The lever 19 is pivotally connected at the rear end, as at 26, with the right-hand side of the bed 9, and extends forwardly beyond the front side of 70 said bed, and said lever has a pin 27 project- ing outwardly therefrom intermediate of the ends thereof. The trip 20 is pivotally connected at 28 with the bed 9 in supporting re- lation to the pin 27, and a spring 29 is ar- ranged to retain said trip always in contact 75 with said pin. Normally the pin 27 rests either in the angle between the two arms of the trip 20, as shown in Fig. 10, or in a notch 30 in the upwardly-extending arm of 80 said trip. The dog 25 is pivotally connected at 31 with the arm 21, and has, besides a downwardly-extending finger, an upwardly- 85 extending finger 32 yieldingly held, by means of a spring 33, in contact with a lug 34 on said arm. The upper end of the trip 20 is in the path of the dog 25.

The link 23 is mounted at its front end on the pivot 31, and has a hook at its rear end to engage a pin 35 carried by the arm 16. The pivot 31 and the pin 35 are at the lower ends of their arms, respectively. The dog 24 at its front end is also mounted on the pivot 31. This dog is provided underneath with a spring-pressed shoe 36, 90 which is pivotally connected at 37 with said dog. The shoe 36 is a new element rendered necessary in order to avoid break- age or other injury to certain of the parts 95 and members, under certain conditions, as will hereinafter be explained. There is a lon- gitudinal slot 38 in the bottom of the dog 24 to accommodate the shoe 36, and the upper 100 surface of said shoe is shaped to enable a certain amount of independent movement to take place between said dog and said shoe. A spring 39 is located between the dog 24 and the shoe 36, back of the pivot 37, and nor- mally disposes the dog so that the rear end 105 thereof is well below the corresponding end of the dog. At this the rear end of the dog 24 is a lug 40 to rest and ride on the upper 110 edge of the lever 19.

When the mechanism just described, which 115 is operating mechanism for the work holder, is disposed as in Fig. 10, the rearward move- ment of the rocker arm 16 imparts, through the medium of the link 23, a corresponding move- ment to the rocker arm 21, the lug 40 then riding rearwardly on the lever 19. The 120 link 23 does not, however, cause the arm 21 to be rocked when the arm 16 is rocked for- wardly from the position shown in Fig. 15. During the rearward movement of the parts, the dog 25 is carried into a position behind 125 the trip 20. In the event the trip 20 be in the path of the dog 25 when said dog moves rear- wardly, the latter snaps past the former. Now, when the lever 19 is swung upwardly 130 on its pivot 26, the shoe 36 is elevated and

causes the dog 24 to swing upwardly on the pivot 31 until the rear end of said dog is in front of the pin 35. At the same time the trip 20 rocks on its pivot 28 and receives the pin 27 in the notch 30, thus supporting the lever 19 in its raised position and the dog 24 in operative position between the pivot 31 and the pin 35. Next, upon the forward movement of the arm 16, the dog 24 causes the arm 21 to be rocked in the same direction, moving from the position illustrated in Fig. 15 to that illustrated in Fig. 10. At this time the dog 25 encounters the trip 20 and rocks the same to permit the pin 27 to pass from the notch 30 into the angle between the arms of said trip, and the lever 19 to swing down again. The dog 24 swings down with the lever 19, from the position in front of the pin 35.

Should, at this time, the arm 21 be disposed with its lower end so close to the lower end of the arm 16 that the dog 24 could not be swung upwardly into place in front of the pin 35, and at the same time the lever 19 be swung upwardly, said dog would strike against said pin from beneath and interfere with the forward movement of said second-named arm, necessary to the proper relative positioning of the members again, were it not for the fact that the spring 39 then yields and permits the rear-end portion of said dog to be forced down, by the moving parts above, towards the corresponding end of the shoe 36, until said pin passes clear of said dog. Thus damage and breakage are prevented that otherwise might occur.

We will now describe the new work holder and other auxiliary elements, and explain the manner in which they function or operate.

Resting on the bed 9 is a bed 41. The bed 41 is held in place by bars 42 and 43 fastened to the bed 9 by screws or other means on the left- and right-hand sides, respectively, of said first-named bed, and two pairs of bolts 44 which pass through slots 45 in said first-named bed into threaded openings in said second-named bed. There are two pairs of slots 45 arranged parallel to the bars 42 and 43, with one slot in front of the other in each pair. Projecting downwardly from the front side of the bed 41 is a perforated lug 46, and a screw-threaded stud 47 extends from the front side of the bed 9 through said lug. On the stud 47 in front of and behind the lug 46 are nuts 48-48.

Upon loosening the bolts 44 and one of the nuts 48, and screwing the other nut 48 on the stud 47 against the lug 46, the bed 41 is moved for adjustment on the bed 9, either outwardly or inwardly, accordingly as the inner nut or the outer nut be turned to move said lug and with it said first-named bed. The bed 41 slides between the bars 42 and 43. After the adjustment has been made the

bolts 44 and the loose nut 48 are retightened.

The stud 22 is mounted in a bearing 49 in front of the bearing 13 on the bed 41, and extends out over the right-hand edge of said bed to receive the rocker arm 21, and a 70 collar 50 which holds said arm on said stud. The arm 21, like the arm 16, extends down between the right-hand side of the bed 9 and the shelf 12. An ordinary pin 51, for taking up wear between the stud 22 and the hub of the 75 arm 21, is provided, said pin being screw-threaded at the upper terminal to receive a nut 52. The tightening of the nut 52 on the pin 51 draws said pin tightly against the stud 22 and increases the frictional resistance 80 between said stud and the arm hub.

A bearing 53 is located on the bed 41, parallel with and a short distance back from the front edge of said bed, and bolted or otherwise secured to the top of said bearing is a 85 short cap 54 and a long cap 55. A hollow rock shaft 56 is journaled in the bearing 53 beneath the cap 55. Within the shaft 56 is a shaft 57. A trunnion 58 of a hollow cylinder 100 is journaled in the bearing 53 beneath the cap 54. The caps 54 and 55 are spaced apart, as also are the shaft 57 and trunnion 58. The trunnion 58 is secured to the shaft 56 by means of a wedge 59 which passes transversely through said shaft and 90 trunnion.

At the inner end of the shaft 57 is a cam 60. The shaft 57 extends outwardly over the bracket 12, and extending radially from said shaft adjacent to the outer end thereof is a 100 pin 61. A crank arm or handle 62 has a hub 63 which is mounted on the outer terminal of the shaft 57, and is notched, as at 64, in the outer side to receive the pin 61. Means are thus afforded for rotating the shaft 57 by 105 hand. The hub 63 may be moved inwardly on the shaft 57 until the notched portion thereof is clear of the pin 61, when the handle 62 is permitted to rest inactively against the front edge of the bracket 12. This is the normal position of the handle 62. The shaft 57 directly in front of the hub of the arm 21 is provided with a pinion 65. This pinion may be formed by cutting teeth directly in the shaft 57. The hub of the arm 21 is provided with a segmental-gear 66 which intermeshes with the pinion 65. Mounted on and keyed at 67 to the hollow shaft 56, inside of the segmental-gear 66, is a hub 68 of a rocker arm 69. The hub 68 is split and the split parts are clamped on the shaft 56 by means of a bolt 70 and nut 71, in the usual manner. 110 An annular groove 72 is provided in the shaft 57 to receive the inner terminal of a radial pin or screw 73 that extends through the hub 68, is tapped into the shaft 56, and extends into said groove. The screw 73 assists the key 67 in rigidly securing or fastening together the shaft 56 and the hub 68, and in holding the parts against endwise 115

120 125 130

movement. A link 74 has one end pivotally connected at 75 with the arm 21 above the pin 31, and the other end pivotally connected at 76 with the arm 69.

From the foregoing it is clear that, when the arm 21 is rocked rearwardly, the segmental-gear 66 actuates the pinion 65 and rotates the shaft 57 with its cam 60, and, through the medium of the link 74, said arm 21 carries with it the arm 69, and said last-named arm rocks the shaft 56 to which said last-named arm is rigidly attached; and, that, when said first-named arm is rocked forwardly, said two shafts are actuated in the opposite direction to that in which they were previously actuated. The segmental-gear 66 is of such length and the amount of movement imparted to the arm 21 is sufficient to cause the pinion 65 to make at least one complete revolution, first in one direction and then in the other, when said arm is oscillated.

A rocker 77 has a hub 78 which is mounted on the hollow shaft 56 and keyed thereto at 79. The hub 78 encircles that portion of the shaft 56 within which is located the cam 60, and the bearing 53 is recessed at 80 to accommodate said hub. The hub 78, being in the recess 80, is held and holds the shaft 56, to which said hub is keyed, against endwise movement. A plunger pin or bar 81 is arranged radially in the shaft 56 and the hub 78, and bears at the inner end on the cam 60. Bearing on the outer end of the bar 81 is the free terminal of a stiff flat spring 82 which will presently be described in detail.

The rocker 77 is bifurcated at 83 to form a work-locating arm 84 and a shorter, clamp-carrying arm 85, the latter being in front of or above the former, according to the position of said rocker. Secured to opposite sides of the arm 84 are two plates 86, the forward or upper edges of which, according to the position of the rocker, and the intermediate side portions of the arm 84 corresponding with one side of the work carried by this holder, and together constituting a locating surface for said work. The plates 86 are made of steel and so protect from wear the intermediate surface or surfaces of the arm 84.

This holder is designed to handle hinged leaves, such as is represented at 87, and securely and rigidly to hold one of these leaves in place while the longitudinal edges thereof and the edges of the recess in one end thereof are being broached. The locating surface above referred to is shaped and proportioned to have placed thereagainst the side of the hinge leaf 87 in which is the depression formed by the bend therein, and to provide a suitable support for said leaf when placed on said surface, with the lower end of the leaf resting on a pin 88 which projects from said surface. The pin 88 is set in the arm 84 at the proper place to support the lower end of

the leaf so that the angle therein coincides with the angle in the locating surface. The arm 85 is slotted, as indicated at 89, to receive a clamp 90 which is pivotally connected at 91 with said arm. The terminal portion of the spring 82, which is opposite to the terminal portion of said spring that bears or is adapted to bear on the plunger bar 81, is secured, by means of a clamping plate 92 and two bolts 93, to the forward or upper edge of the clamp 90. The clamp 90 is equipped with an equalizer 94 which is pivotally connected at 95 with said clamp. The equalizer 94 is bifurcated to receive a portion of the clamp 90, and those parts of said equalizer which are adjacent to the locating surface of the arm 84 are adapted, by reason of their shape and proportions, to fit the side of the leaf 87 which is exposed when said leaf is first placed in position on said arm and the pin 88.

When the plunger bar 81 is thrust outwardly by the high part of the cam 60, it causes, through the medium of the spring 82, the clamp 90 to be rocked on its pivot 91, with a powerful yet yielding movement, in a manner to carry the equalizer 94 into contact with the leaf 87, and to force said equalizer tightly against said leaf, thereby clamping the same securely in position ready to be broached. When the high part of the cam 60 passes from beneath the bar 81, said bar, which previously was forced outwardly by said cam, is forced inwardly by the spring 82, and the clamp 90 is rocked on the pivot 91 in the direction to carry the equalizer 94 away from the leaf 87, thus releasing said leaf. The spring 82 prevents jar and shock when the equalizer 94 is forced into clamping position relative to the leaf 87, but at the same time affords all the power needed to hold said leaf in place while being broached.

The arm 84 with its wear plates 86, and the equalizer 94, must not be wider than the leaf 87, in order that said arms and equalizer shall clear the side broaches 6. The plates 86 extend beyond the free end of the arm 84 to afford the necessary support for the leaf and clearance for the broach 5, which broach has front and side teeth to cut the three sides of the leaf slot. The space between the plates 86 is sufficiently wide to admit of the passage through the same of the broach 5, so also is the space between the sides, at their outer ends of the equalizer 94. The outer end of the cross piece (136) of the equalizer also is back far enough, when the work holder is in broaching position, to clear the central broach.

A housing 109 constitutes a part of the present invention, and two wings or guides 157 are attached to the sides of said housing, directly above the recess between the arms 84 and 85, when the rocker 77 is in loading position, and spaced apart a distance approxi-

mately equal to that of an unbroached leaf. The purpose of the guides 157 is to assist the operator in placing the leaf on the locating surface of the arm 84, and insure the placing of said leaf on said surface with equal amounts of longitudinal edge portions of the leaf projecting beyond said surface. The upper edges of the guides 157 are some distance below the top of the leaf when in place on the locating surface, consequently said guides do not interfere with the thumb and fingers of the operator when placing the leaf in the holder.

An adjustable positioning bolt 96 is provided to be contacted with by the spring 82, when the bar 81 rides onto the low part of the cam 60, and prevents the clamp 90 from swinging inwardly at the top and locating the equalizer 94 in the way of a leaf 87 being introduced into the holder. Due to the fact that for an instant, while the bar 81 is riding from the high part onto the low part of the cam 60, the spring 82 is not held either by said bar or the bolt 96, a spring 97, Fig. 10, is placed in the slot 89 and interposed between the bottom of said slot and the adjacent edge of the clamp 90 at a point below or behind the pivot 91, according to the position of the rocker 77. The spring 97, having a constant tendency to rock the lower or rear end of the clamp 90 outwardly, causes the spring 82 to be swung against the bolt 96 as soon as said last-named spring ceases to be held under tension by the bar 81.

While the hollow shaft 56 is being rocked in the direction to carry the rocker 77 rearwardly, or from loading position to broaching position, the shaft 57 is caused to rotate and carry the high part of the cam 60 beneath the bar 81, and the parts are so timed, that, before said rocker arrives in broaching position, the spring 82 is brought under maximum tension by said cam and said bar, and the leaf 87 is firmly and securely clamped between the arm 84 and the equalizer 94, and, directly after said rocker begins to move forwardly into loading position again, said bar rides onto the lower part of said cam and relieves the tension on said spring, thus bringing about the release of said leaf.

The rearward and downward movement of the rocker 77 is limited by a rest or pillow-block 98 secured by means of screws or otherwise to an upstanding support 99 on the bed 41. The member 99 positions the pillow-block 98 at the proper elevation to receive and support the rocker 77 in a manner properly to present the leaf 87 carried by said rocker to the broaches 5 and 6.

When the rocker 77 is forward in loading position, the equalizer 94 is located with its then lower end near enough to the locating surface of the arm 84 to assist in

guiding the leaf 87 onto the pin 88, and to prevent said leaf from becoming disengaged from said pin, while the clamping and unclamping operations are taking place.

In the casing or cylinder 100 is a plunger or latch 101, and said latch has an angular base that projects below the bottom of said cylinder, and is adapted to engage a block 102 secured by means of screws or otherwise to the bed 41. The latch 101 has a passage which opens into the same from above, and located in said passage, between the bottom thereof and a cap 103 screwed into the top of the cylinder 100, is a spring 104. The spring 104 tends constantly to retain the latch 101 with its angular base in contact with the block 102. A screw 105 is tapped into the front side of the cylinder 100, and at its inner end enters a vertical groove 106 in the adjacent side of the latch 101, and thus said latch is held against rotation in said casing, but is free to move up and down therein. The block 102 has two bearing surfaces 107 and 108 for the angular base of the latch 102, said surfaces being so related to each other and to said base that, when the rocker 77 is in its rearward position, one part of said base is in engagement or contact with the surface 107, and, when said rocker is in the forward position, the part of said base is in engagement or contact with the surface 108, as shown in Fig. 3. The cylinder 100, being rigidly connected, by means of the trunnion 58 and the wedge 59, to the shaft 56, is rocked with said shaft and so causes the spring-pressed latch 101 to snap into engagement first with one of the latch-block surfaces (107 and 108), and then with the other of said surfaces. The action or effect of the latch on the rocker is, of course, through the shaft 56. The purpose of the latch is to assist in maintaining the rocker in either of its extreme positions, in preventing rebound or back-lash, and in stabilizing generally the movement of the rocker between the two extremes of its field of operation.

The contact bolt 96 for the spring 82 is tapped into and through the front side of the housing 109, said bolt being provided with a set-nut 110 as usual, outside of said housing.

The hub 78 and the lower portion of the rocker 77 are wider than the upper portions of said rocker, and wider than the arms 84 and 85, and these wide portions are received between upwardly-extending wings 111 at the inner ends of the bearing caps 54 and 55. The housing 109 has rearwardly-extending parts 112 which are mounted on and bolted to the caps 54 and 55 on both sides of the wings 111. The housing 109 at the bottom in front is bolted at 113-113 to the front side of the bearing 53. There is an opening

114 in the front side of the housing 109, near the bottom thereof and between the parts of said housing that are bolted to the bearing 53, and said housing is open behind. 5 A plate 115 forms the top of the housing 109, and may be secured to the sides and front of said housing by means of screws or otherwise.

A shaft 116 is journaled under the plate 10 115 in the sides of the housing 109, parallel with the front thereof, and a pinion 117 is mounted on and secured to said shaft. The pinion 117 intermeshes with a rack 118 on the under side of a safety bar 119, which bar is 15 slidingly arranged in the sides of the housing 109 beneath the plate 115 and at right-angles to the shaft 116, as best shown in Fig. 7. The bar 119 is of sufficient length and so positioned that, when actuated rearwardly, it passes 20 above the top of the leaf 87 when in proper position in the holder, but encounters said leaf and has its rearward movement thereby checked, in the event the leaf is not in such position or fully seated in said holder. The 25 shaft 116 extends beyond its bearings in the sides of the housing, and is held against longitudinal movement in said bearings by a collar 120 secured to the left-hand terminal of said shaft and a hub 121, of a lever or arm 30 122, outside of said bearings. At 123—123 are represented ways or guides with which the sides of the housing 109 are provided for the bar 119. The rear-terminal portion of the bar 119 must be narrower than the space 35 between the sides of the equalizer 94, so as to avoid interfering or being interfered with by said equalizer.

Having its upper terminal bifurcated and pivotally connected at 124 with the operating 40 arm 122 is a vertical rod 125. The rod 125 extends downwardly through an opening, as 128, in the bed 41, and is yieldingly retained in its low position by means of a collar 126 secured to said rod below said bed, and a spring 45 127 mounted on said rod between said collar and the bottom edge of said opening. The opening 128 is wider from front to back than between its sides, and so affords room for whatever forward and backward movement 50 there may be on the part of the rod 125, when the same and its connections are actuated. The downward movement of the arm 122, and consequently of the rod 125, is limited by the bottom (158) of the bifurcation at the top 55 of said rod, against which said arm stops and in contact with which it normally remains, when the arm is swung downwardly on the shaft 116—see Fig. 10.

A horizontal bracket 129 is bolted or otherwise secured to the front side of the bed 9, and this bracket is provided with two forwardly-projecting bearings 130 for a horizontal rock shaft 131. Mounted on and secured to the shaft 131, outside of the bearings 130, are two rocker arms 132. At their

free ends the arms 132 carry a rod 133. In the lower-end portion of the rod 125 is a longitudinal slot 134, and the inner end of the rod 133 extends through said slot. The outer end of the rod 133 extends through a suitable opening provided to receive the same in the lever 19 at the front end. 70

Upon grasping the arm 122 and swinging said arm upwardly, the shaft 116 with the pinion 117 thereon is partially rotated in the direction to actuate the rack 118, with which said pinion intermeshes, rearwardly, and with said rack the safety bar 119. If the leaf 87 is properly seated at this time, the bar 119 is permitted to move rearwardly until the rack 118 encounters a stop pin 135 which projects inwardly from one side of the housing 109 back of said rack, the rear-end portion of said bar then being above said leaf. In the event, however, that the leaf 87 be not fully seated with the lower end on the pin 88, the upper-end portion of said leaf is in the path of the bar 119, and said bar is thereby prevented from making its full rearward stroke, with the result that the arm 122 can not be 85 swung upwardly far enough to reset the dog 24 and cause the rocker 77 to be thrown into broaching position. But upon subsequently positioning the leaf 87 to clear the way for the bar 119, the arm 122 can be raised to the 90 full extent. The lever 122, when swung upwardly, carries with it, against the resiliency of the spring 127, the rod 125, and said rod in turn carries with it the rod 133 mounted in the rocker arms 132 on the rock shaft 131, and the upward movement of said last-named rod causes the lever 19 to swing upwardly on the pivot 26. This movement of the lever 19, provided the arm 122 be raised to the full extent, swings the dog 24 upwardly into operative position in front of the pin 35, and the arm 21 is operated to bring about clamping the work and movement of the same into position to be operated on by the broaches. The slot 134 in the rod 125 permits said rod to descend as soon as the arm 122 is released, and also enables the lever 19 to be moved up and down independently in said rod, it being understood that, when the rod is normally disposed and the lever 19 in its low position, the rod 133 is in the bottom of the slot 134. The downward movement of the rod 125 and the arm 122 causes the safety bar 119, through the medium of the shaft 116, the pinion 117, and the rack 118, to be moved forward to clear the way from above to the entrance to the space between the locating arm 84 and the equalizer 94. 110

To facilitate the removal of the work from the holder after said work has been broached, we provide an extractor which is attached to and travels with the ram 3. This extractor comprises two movable jaws 137 spaced apart and having their adjacent edges serrated, as shown in Fig. 14. The jaws 137 are arranged 125 130 135

in a carrier 138 which is movably connected with and supported from a bracket 139 bolted or otherwise secured to the ram 3 at the top. The bracket 139 extends forwardly from the ram 3, and has at the front end a bearing sleeve 140 for a vertical stem 141 that rises from a lug 142 on the back side of the carrier 138. The upper terminal of the stem 141 is screw threaded to receive checknuts 143 above the sleeve 140, which nuts limit the downward movement of said stem, and may be adjusted to increase or decrease the amount of such movement. Encircling the stem 141, between the bottom of the sleeve 140 and a collar 144 adjustably secured to said stem by means of a bolt 145, is a spring 146 which has a constant tendency to force the stem downwardly as far as permitted by the nuts 143. In the event the extractor meets with resistance sufficient to overcome the force of the spring 146, the latter yields and permits the stem 141 with the attached parts to move upwardly, thus avoiding undue shock or jar and breakage. The stem 141 is prevented from 25 rotating on its axis in the sleeve 140, by means of a bolt 147 that is tapped into the front side of said sleeve, and has its inner end received in a vertical groove 148 in the corresponding side of said stem. The bolt 147 does not interfere with the movement of the stem 141 lengthwise. By the means just described, the carrier 138 is supported with its front side parallel with the front of the machine, and directly above the locating arm 30 84 when the rocker 77 is in loading position, and the jaws 137 are positioned in and by said carrier to receive between them the leaf 87 supported by said arm when the latter is in the aforesaid position, as will presently more clearly appear.

Secured by means of screws or otherwise to the front of the carrier 138 is a cover plate 149, and within said carrier behind said plate is a chamber 150 which opens through the bottom of said carrier, and has side edges forming guides that converge from above downwardly, one of which appears at 151 in Fig. 14. In the top of the carrier 138 is a slot 152 sufficient in size to permit a leaf (87) to pass freely through the same. The slot 10 opens into the chamber 150 above the space between the jaws 137. Slidingly arranged in the top of the carrier 138, each side of the slot 152, and having the same inclination as that of the adjacent guide 151, is a rod 153. Secured to the upper-end portion of each rod 153, above the top of the carrier 138, is a collar 154 which limits the downward movement of said rod. The lower terminal of 55 each rod 153 is inserted in the upper end of one of the jaws 137, and secured thereto by means of a transverse pin 155. Encircling each rod 153, between the top of the jaw 137 attached to said rod and the top of the chamber 150 is a spring 156, which has a constant

tendency to force said jaw and said rod downwardly as far as the collar 154 permits. The outer, inclined edge of each jaw 137 is ribbed to fit the contiguous guide 151.

When the jaws 137 are in the lowest position permitted by the collars 154, they are closest together, and when said jaws are forced upwardly they separate or are disposed more widely apart. The serrated edges of the jaws are always approximately parallel.

Normally the jaws 137 are so disposed, by the yielding supporting members therefor, that the space between them is a little less than the width of the broached leaf 87. This insures a sufficiently tight engagement with the leaf by the jaws.

As the ram 3 approaches the extreme lower end of its travel, and after the dog 11 has caused the work holder to be thrown forward into broaching position, and the broached leaf to be unclamped, the jaws 137 are carried into contact and engagement with the longitudinal edges of said leaf. Where the jaws 137 at their lower ends encounter the leaf 87, the jaws are forced upwardly slightly, against the resiliency of the spring 156, and separate to receive between them said leaf. The jaws descend some distance on the leaf, and grip the same with sufficient force to raise it out of the holder, when said jaws are carried upwardly, as they are immediately upon the reversal of the movement of the ram 3. The leaf remains in the grasp of the jaws 137 until they are carried downwardly again with the ram, when the leaf in the grip of the jaws encounters the leaf last inserted in the holder, and said first-named leaf is knocked out of engagement with the jaws which continue to descend until they grasp said last-named leaf preparatory to withdrawing it from the holder upon the next upward movement of the ram. In Fig. 14, two leaves are shown in the grasp of the jaws, as they appear just before the upper leaf is dislodged or knocked out by the lower leaf. By providing the machine with this extractor as an auxiliary to the work holder, it is necessary for the leaves to be actually handled by the operator only for the purpose of placing or setting said leaves, one after another, in the holder.

The complete operation of the mechanism hereinbefore described, starting with the movable parts disposed as in Figs. 1, 7, and 10, is described as follows:

When the dog 10 carried by the ram 3, which ram is descending, encounters the roll 18, the arm 17 is rocked forwardly and the arm 16 rearwardly, and, through the medium of the link 23, the arm 21 is also rocked rearwardly. This movement of the arm 21 rocks the rocker 77 forwardly into the loading position shown in Figs. 8 and 15, and rotates the shaft 57 and its cam 60 to the extent required to re-

lieve the tension on the spring 82 and thus release the leaf 87 which has just been broached. The ram 3 travels downwardly a sufficient distance, after the dog 10 has acted 5 on the arm 17, or has a sufficient amount of overrun, to carry the extractor jaws 137 into gripping relationship with the aforesaid leaf. The ram 3 is now reversed and commences to move upwardly, when the jaws 137 remove 10 the finished leaf from the holder. Then the operator inserts a second leaf in the holder, grasps the handle 122, and swings it upwardly. The rod 125 is elevated with the arm 122, against the resiliency of the spring 127, and causes the lever 19 to be swung upwardly, 15 and to locate the dog 24 in operative position in front of the pin 35, in which position said dog is held by said lever, because the latter is now supported in elevated position by the 20 trip 20. The parts, however, fail to locate the dog 24 in operative position, in the event the leaf last inserted in the holder projects into the path of the safety bar 119, as hereinbefore explained. After raising the arm 122, it is released and swings downwardly, by gravity 25 and under the influence of the spring 127 which carries the rod 125 downwardly until said arm encounters the stop 158 formed by the bottom of the slot in the upper terminal of 30 said rod. Next, as the ram approaches the upper end of its travel, the dog 11 encounters the roll 18 and actuates the arm 17 rearwardly and the arm 16 forwardly, and with 35 said last-named arm the arm 21 forwardly, through the medium of the dog 24. The forward movement of the arm 21, through the medium of the cam 60 and the spring 82, brings about the clamping of the leaf last 40 placed on the locating arm 84, and immediately causes the rocker 77 to be rocked rearwardly and downwardly onto the pillow-block 98, whereby said leaf is positioned in the paths of the broaches 5 and 6, ready to be 45 acted on by said broaches when next the ram descends. At the end of the upward travel 50 the ram is reversed and descends, and the broaches carried by said ram make the necessary cuts on the leaf held in their paths. The descending dog 10 brings about a reversal of the work holder and parts, and 55 also causes the leaf in the extractor to be knocked out, when said leaf contacts with the leaf last finished, and causes said extractor to grasp said lastly-finished leaf. The lastly-finished leaf is withdrawn by the 60 extractor from the holder, as soon as the ram again commences to ascend. At the time the arm 21 is swung forwardly, the dog 25 knocks the trip 20 from beneath the pin 27, and the 65 lever 19 is permitted to swing downwardly again. The dog 24 swings downwardly with the lever 19, and is thus removed from active or operative to inactive or inoperative position.

65 In the event the work holder be not loaded

ready to be moved into broaching position, at the time the ram arrives at the upper end of its travel, the lever 19 is left in its low position and with it the dog 24, and the arm 16 is actuated, by the action of the dog 11 on 70 the roll 18 and the arm 17, forwardly, without affecting the arm 21 and said holder.

The work-clamping and -holding members can be actuated or operated by hand, whenever occasion requires, simply by moving the 75 handle 62 outwardly to engage the notched part of its hub with the pin 61, which is the condition shown in the drawings, and rotating the shaft 57 by means of said handle. The link 23 permits the arm 21 to be swung 80 freely rearwardly, when the mechanism is disposed as in Fig. 10, and then as freely forwardly, assuming that the dog 24 is down.

The rocker 77 is preferably provided, on the sides between the axis and the arms 84 85 and 85, with troughs 159—159. The troughs 159 are formed in the upper edges of the thicker, hub portion of the rocker 77, and arranged to catch the oil and particles cut from the work, and convey the same away from 90 the bearing parts of and for said rocker, thus preventing clogging of said parts, and undue wear of rubbing or contiguous surfaces, such as the surfaces between the hub 78 and the wings 111.

Hinge leaves and other work of different shapes and sizes require that the locating surface and equalizer work-engaging surfaces be changed accordingly, and to correspond with the new shape and size in each 100 case.

In Figs. 16 and 17 is illustrated mechanism that may be provided for driving and reciprocating the ram 3, and the same is briefly described as follows, although it is 105 to be understood that the ram may be driven and reciprocated by means of any one of various other mechanisms.

An electric motor 160 is mounted on a bracket 161 which extends to the right from 110 the bed 9 adjacent to the rear end thereof, and a transmission case 162 is mounted on said bed near said end. The motor 160 has a shaft 163 with a gear 164 thereon at the inner terminal, and said gear intermeshes 115 with the gear 165 on the adjacent terminal of a shaft 166 journaled in the case 162, both of these shafts being transversely arranged relative to the machine. A longitudinal shaft 167, on the front end of which the pinion 8 is mounted, is journaled in suitable bearings in the bed 9, extends into the case 162, and is driven from the motor 160, through the medium of the shafts 163 and 166, the intermeshing gears 164 and 165, and 120 the transmission in said case, which transmission is here represented as comprising intermeshing spiral gears 168 and 169 mounted on said shaft 166 and the shaft 167, respectively. A box 170 is located on the shelf 12 125 130

adjacent to its rear end, for motor-reversing mechanism connected by suitable electrical conductors with the motor 160. This reversing mechanism is such as is commonly employed for such purposes, and includes a shaft 171 which projects beyond the left-hand side of the box 170, and a gear 172 secured to said shaft on the protruding terminal thereof. A reversing rocker arm 173 is mounted on the shaft 15, and has at its rear end a toothed segment 174 which intermeshes with the reversing-mechanism gear 172, said arm being forward of said gear.

The arrangement, construction, and timing of parts are such that, when the arm 17 is rocked rearwardly, the arm 173 is rocked downwardly and corresponding motion is imparted to the gear 172 by means of the toothed segment 174; and, when said arms 20 are rocked in the opposite directions, said segment imparts motion in the opposite direction to said gear. At each movement thus imparted to the gear 172 the motor 160 is reversed and consequently the direction of 25 the ram 3 is changed.

In the present example the arm 173 is mounted on the shaft 15 between the bearing 18 and the hub of the arm 17.

More or less change in the shape, size, construction, and arrangement of some or all of the parts of this work holder and associated mechanism, in addition to those hereinbefore specifically pointed out, may be made without departing from the spirit of 35 our invention, or exceeding the scope of what is claimed.

What we claim as our invention, and desire to secure by Letters Patent, is—

1. In operating mechanism for a work holder, oscillatory arms, connecting means between said arms whereby one when actuated in one direction actuates the other, a movable member adapted to be moved into and out of operative position between said arms, whereby the movement of the first arm in the opposite direction is imparted to the second arm when said member is in operative position, means to support said member in inoperative position and move the same into operative position, and yielding means between said member and said supporting and operating means therefor.

2. In operating mechanism for a work holder, oscillatory arms connected by a link which causes the second arm to be actuated in one direction from the first, but to remain inactive when the first is actuated in the opposite direction, a dog pivotally connected with one of said arms and adapted to be moved into and out of operative position relative to the other of said arms, whereby the second arm may be moved by the first arm in the aforesaid opposite direction, said dog being provided with a pivotally connected spring-pressed shoe, and a member

on which said shoe rides, said member being adapted to move said dog into operative position and to permit said dog to move out of such position.

3. In operating mechanism for a work holder, oscillatory arms connected by a link which causes the first arm to move the second arm in one direction, a dog pivotally connected with one of said arms and adapted to be moved into and out of operative position relative to the other of said arms, whereby movement in the opposite direction may be imparted to said second arm from said first arm, a pivotally mounted lever to support said dog and move the same into and out of operative position, a pivotally mounted arm, a rod pivotally connected with said arm, and connecting means between said lever and said rod, whereby the lever is swung upwardly when the rod is carried upwardly by said arm.

4. In operating mechanism for a work holder, oscillatory arms connected by a link which causes the first arm to move the second arm in one direction, a dog pivotally connected with one of said arms and adapted to be moved into and out of operative position relative to the other of said arms, whereby movement in the opposite direction may be imparted to said second arm from said first arm, a pivotally mounted lever to support said dog and move the same into and out of operative position, a pivotally mounted arm, a rod pivotally connected with said arm, said rod having a longitudinal slot in the lower-terminal portion thereof, a suitably-journalled rock shaft provided with arms, and a rod carried by said arms, said last-named rod being pivotally connected at one terminal with said lever and extending at the other terminal into said slot.

5. In mechanism of the class described, a work holder, mechanism to actuate said work holder from loading position to broaching position, and means to render said mechanism operative when the work is fully seated in said work holder, said means comprising an arm and a shaft for said arm, a safety bar provided with a rack and slidably arranged in position to encounter the work when not fully seated in said work holder, and to clear said work when fully seated, and a pinion carried by said shaft and intermeshing with said rack, the construction and arrangement of parts being such that, when said bar meets with no opposition, said arm can be operated to an extent sufficient to render said mechanism active, but, when said bar encounters the work, the movement of the bar is checked and the movement of said arm correspondingly limited, whereby said mechanism fails to be rendered operative.

6. In mechanism of the class described, a work holder provided with clamping means, mechanism to actuate said work holder from

- loading position to broaching position, and to cause said clamping means to engage the work, and means to render said mechanism operative when the work is fully seated in 5 said work holder, said means comprising an arm and a shaft for said arm, a safety bar provided with a rack and slidably arranged in position to encounter the work when not fully seated in said work holder, and to clear 10 said work when fully seated, and a pinion carried by said shaft and intermeshing with said rack, the construction and arrangement of parts being such that, when said bar meets with no opposition, said arm can be operated 15 to an extent sufficient to render said mechanism active, but, when said bar encounters the work, the movement of the bar is checked and the movement of said arm correspondingly limited, whereby said mechanism fails 20 to be rendered operative.
7. In a work holder, an oscillatory member provided with a receiving and positioning arm for the work, a movable clamp carried by said member to cooperate with said arm in 25 securing the work in place, and means automatically to cause said clamp to engage the work when said member is rocked in one direction, and to release the work when said member is rocked in the opposite direction.
- 30 8. In a work holder, an oscillatory member provided with a receiving and positioning arm for the work, a movable clamp provided with a movable equalizer, carried by said member to cooperate with said arm in securing 35 the work in place, and means automatically to cause said clamp to engage the work when said member is rocked in one direction, and to release the work when said member is rocked in the opposite direction.
- 40 9. In a work holder, an oscillatory member provided with a receiving and positioning arm for the work, a clamp carried by and pivotally connected with said member to cooperate with said arm in securing the work in 45 place, said clamp being provided with a pivotally connected equalizer and means automatically to cause said clamp with said equalizer to engage the work when said member is rocked in one direction, and to release the 50 work when said member is rocked in the opposite direction.
10. In a work holder, an oscillatory member provided with a receiving and positioning arm for the work, a movable clamp carried by said member to cooperate with said arm in securing the work in place, and yielding means to cause said clamp to engage the work when said member is rocked in one direction, and to release the work when said 55 member is rocked in the opposite direction.
11. In a work holder, an oscillatory member provided with a locating member for the work, a clamping member having a part to engage the work on said locating member, 60 a spring rigidly attached to said clamping

member, means to place said spring under tension and rock said clamp into engaging position with the work when said first-named member is actuated in one direction, and to release said spring when said first-named member is rocked in the opposite direction, and means to return said clamping member to disengaging position at the end of said last-named movement of the oscillatory member. 70

12. In a work holder, an oscillatory member provided with a locating member for the work, a clamping member having a part to engage the work on said locating member, a spring rigidly attached to said clamping member, means to place said spring under tension and rock said clamp into engaging position with the work when said oscillatory member is actuated in one direction, and to release said spring when said oscillatory member is rocked in the opposite direction, and means in the path of said spring to cause the same to actuate said clamp out of engaging position with the work, at the end of said last-named movement of the oscillatory member. 80

13. In a work holder, a rock shaft, a rocker arm having integral locating and clamp arms and a clamp movable on said clamp arm. 85

14. In a work holder, a rock shaft, a rocker mounted on said shaft and provided with a locating arm and a clamp arm, a clamp pivotally connected with said second-named arm, and an equalizer pivotally connected with said clamp, said equalizer being adapted to engage the work positioned on said locating arm. 95

15. In a work holder, a rock shaft, a rocker mounted on said shaft, and provided with a locating arm, locating plates secured to opposite sides of said arm and extending beyond the outer end of the same to admit of the passage between them of a broach, edge portions of said plates serving to form in part the locating surface for the work, and means to clamp the work on said surface. 100

16. In a work holder, a rock shaft, a rocker mounted on said shaft, and provided with a locating arm and a clamp arm, a clamp pivotally connected with said clamp arm, an equalizer pivotally connected with said clamp, and adapted to engage the work on said locating arm, parts of said equalizer which engage the work being spaced from each other for the passage of a broach, and operating means for said clamp. 115

17. In a work holder, a rock shaft, a rocker mounted on said shaft, and having a locating arm and a clamp arm, plates secured to opposite sides of said locating arm, forming parts of the locating surface for the work, and extending beyond the outer end of said arm to permit a broach to pass between them, a clamp pivotally connected with said clamp arm, an equalizer pivotally connected with 120

- said clamp, said equalizer being adapted to engage the work on said locating surface, and having parts spaced from each other for the passage therebetween of said broach, 5 and operating means for said clamp.
18. In a work holder, a rock shaft, a rocker mounted on said shaft, and provided with a locating arm and a clamp arm, said rocker and arms being integral, a clamp pivotally connected with said clamp arm, an equalizer pivotally connected with said clamp, and having a part to assist in supporting the work when the same is placed on said locating arm, and means to actuate said clamp 10 and cause said equalizer to engage the work and securely hold the same in position on said locating arm.
19. In a work holder, an oscillatory member provided with work-engaging and releasing means, and yielding means to assist in holding said member in either of its extreme positions and operable as the member reaches an extreme position.
20. In a work holder, an oscillatory member provided with work-engaging and releasing means, and a spring-pressed latch to assist in holding said member in either of its extreme positions.
21. The combination, in a work holder, 25 with a suitably journaled rock shaft, a rocker secured to said shaft, and provided with locating and clamping means for the work, and an arm also secured to said shaft, of an operating arm, a link connecting said arms, and means to actuate said operating arm.
22. The combination, in a work holder, 30 with a suitably journaled rock shaft, a rocker secured to said shaft, and provided with locating and clamping means for the work, an arm also secured to said shaft, an operating arm, a link connecting said arms, and means to actuate said operating arm, of yielding means to assist in holding said shaft with said rocker at either end of the movement thereof.
23. The combination, in a work holder, 35 with a suitably journaled rock shaft, a rocker secured to said shaft, and provided with locating and clamping means for the work, an arm also secured to said shaft, an operating arm, a link connecting said arms, and means to actuate said operating arm, of a cylinder secured to said shaft at one end, a spring-pressed latch in said cylinder and 40 projecting therefrom, and a block having surfaces adapted to be engaged by said latch when in either of its two extreme positions.
24. In a work holder, a suitably journaled hollow rock shaft, a rocker secured to said shaft, a clamp pivotally connected with said rocker, a shaft journaled in said hollow shaft, actuating means for said shafts, and means operated by said second-named shaft to actuate said clamp into engaging position.
25. In a work holder, a suitably journaled 45 hollow rock shaft, a rocker secured to said shaft, a clamp pivotally connected with said rocker, a spring secured to said clamp, a shaft journaled in said hollow shaft, means to actuate said shafts, and means to actuate said spring from said second-named shaft 50

- hollow rock shaft, a rocker secured to said shaft, a clamp pivotally connected with said rocker, a spring secured to said clamp, a shaft journaled in said hollow shaft, and provided with a cam, a radial member slidingly arranged in said hollow shaft and the hub of said rocker, between said cam and the free terminal of said spring, and operating means for said shafts.
27. In a work holder, a suitably journaled hollow rock shaft, a rocker secured to said shaft, a clamp pivotally connected with said rocker, a spring secured to said clamp, a shaft journaled in said hollow shaft, and provided with a cam, a radial member slidingly arranged in said hollow shaft and the hub of said rocker, between said cam and the free terminal of said spring, and operating means for said shafts.
28. The combination, in a work holder, with a suitably journaled hollow rock shaft, a rocker secured to said shaft, a clamp pivotally connected with said rocker, a spring secured to said clamp, an arm also secured to said shaft, a shaft journaled in said hollow shaft, and provided with a pinion and with a cam, and a radial member slidingly arranged in said hollow shaft and the hub of said rocker, between said cam and the free terminal of said spring, of an operating arm provided with a segmental-gear intermeshing with said pinion, a link pivotally connected with said arms, and actuating means for said operating arm.
29. In a work holder, a suitably journaled hollow rock shaft, a rocker secured to said shaft, a clamp pivotally connected with said rocker, yielding means to assist in holding said shaft and rocker in either extreme position of the same, a shaft journaled in said hollow shaft, actuating means for said shafts and means operated by said second-named shaft to actuate said clamp into engaging position.
30. In a work holder, a suitably journaled hollow rock shaft, a rocker secured to said shaft, a clamp pivotally connected with said rocker, a spring secured to said clamp, yielding means to assist in holding said shaft and rocker in either extreme position of the same, a shaft journaled in said hollow shaft, means to actuate said shafts, and means to actuate said spring from said second-named shaft 130

and cause said clamp to be moved into engaging position with the work.

31. In a work holder, a suitably journaled hollow rock shaft, a rocker secured to said shaft, a clamp pivotally connected with said rocker, yielding means to assist in holding said shaft and rocker in either extreme position of the same, an arm also secured to said shaft, a shaft journaled in said hollow shaft, and provided with a pinion, means to actuate said clamp from said second-named shaft into engagement with the work, an operating arm provided with a segmental-gear intermeshing with said pinion, a link pivotally connected with said arms, and actuating means for said operating arm.

32. In a work holder, a suitably journaled hollow rock shaft, a rocker secured to said shaft, a clamp pivotally connected with said rocker, a spring secured to said clamp, yielding means to assist in holding said shaft and rocker in either extreme position of the same, a shaft journaled in said hollow shaft, and provided with a cam, a radial member slidably arranged in said hollow shaft and the hub of said rocker, between said cam and the free terminal of said spring, and operating means for said shafts.

33. The combination, in a work holder, with a suitably journaled hollow rock shaft, a rocker secured to said shaft, a clamp pivotally connected with said rocker, a spring secured to said clamp, yielding means to assist in holding said shaft and rocker in either extreme position of the same, an arm also secured to said shaft, a shaft journaled in said hollow shaft, and provided with a pinion and with a cam, and a radial member slidably arranged in said hollow shaft and the hub of said rocker, between said cam and the free terminal of said spring, of an operating arm provided with a segmental gear intermeshing with said pinion, a link pivotally connected with said arms, and actuating means for said operating arm.

34. The combination, in a work holder, with a suitably journaled hollow rock-shaft, a rocker mounted on and secured to said shaft, a clamp pivotally connected with said rocker, a spring secured to said clamp, a cylinder rigidly secured to said shaft, a spring-pressed latch carried by said cylinder, an arm secured to said shaft, a shaft journaled in said hollow shaft, and provided with a pinion and with a cam, and a sliding member arranged in said hollow shaft and the hub of said rocker, between said cam and the free terminal of said spring, of an operating arm provided with a segmental-gear intermeshing with said pinion, a link pivotally connected with said two arms, actuating means for said operating arm, and a block having surfaces adapted to be engaged by said latch when in either of its two extreme positions.

35. In a work holder, a rock shaft, a rocker mounted on said shaft, and having locating and clamp arms, said rocker and arms being integral, a clamp pivotally connected with said clamp arm, an equalizer pivotally connected with said clamp, and a spring arranged to bear on said clamp and tend to rock the same on its pivot in the direction to carry said equalizer towards said locating arm.

36. In a work holder, a rock shaft, a rocker mounted on said shaft, and adapted to be moved between loading and broaching positions, and having locating and clamp arms, a clamp pivotally connected with said clamp arm, an equalizer pivotally connected with said clamp, a spring secured to said clamp, means to act on said spring to cause the same to impart to said clamp movement which carries said equalizer towards said locating arm, and a member in the path of said spring to cause the same to rock said clamp in the direction to carry said equalizer away from said locating arm, when said rocker is moved into loading position.

37. In a work holder, a rock shaft, a rocker mounted on said shaft and adapted to be moved between loading and broaching positions, and having locating and clamp arms, a clamp pivotally connected with said clamp arm, an equalizer pivotally connected with said clamp, a spring secured to said clamp, means to act on said spring to cause the same to rock said clamp in the direction to carry said equalizer towards said locating arm, an auxiliary spring tending to rock said clamp in the direction to carry said equalizer towards said locating arm, and a member in the path of said first-named spring to cause said spring to rock said clamp in the direction to move said equalizer away from said locating arm, when said rocker is actuated into loading position.

38. The combination, with a work holder, and means to move said work holder between loading and broaching positions, of means to clamp the work in said holder while the same is moving from loading position to broaching position, and to release said work while said holder is moving from broaching position to loading position.

39. The combination, with a work holder, means to move said work holder between loading and broaching positions, and means to clamp the work in said holder while the same is moving from loading position to broaching position, and to release said work while said holder is moving from broaching position to loading position, of automatic means to withdraw the work from the holder while said holder is in loading position.

40. The combination, with a work holder, and means to clamp the work in said holder and move the same from loading to broaching position, and to move said holder from broaching to loading position and release said

- work, of means movable to and from said holder when in loading position, and adapted to grasp and extract the work when said last-named means approaches and recedes from said holder.
41. The combination, with a work holder, and means to clamp the work in said holder and move the same from loading to broaching position, and to move said holder from broaching to loading position and release said work, of means movable towards said holder when in loading position, and having parts adapted then to grasp the work, and movable away from said holder with the work in the grasp of said parts, said parts being further adapted, when said last-named means is moved again towards said holder, to have said work removed from them by contact of said work with work lastly placed in the holder.
42. In mechanism of the class described, a reciprocating ram, a work extractor carried by said ram, a work holder consisting in part of clamping means for the work, and means operated from said ram to move said holder between loading and broaching positions, said extractor being adapted to act on the work when said holder is in loading position.
43. In mechanism of the class described, a reciprocating ram, a work extractor carried by said ram, an oscillatory work holder consisting in part of clamping means for the work, and means operated from said ram to move said holder between loading and broaching positions, said extractor being adapted to act on the work when said holder is in loading position.
44. In mechanism, of the class described, a reciprocating ram, a work extractor carried by said ram, a work holder consisting in part of clamping means for the work, means operated from said ram to move said holder between loading and broaching positions, and means operated from said ram to actuate said clamping means into engagement with the work when said holder leaves said loading position, and to release the work when said holder approaches said loading position, said extractor being adapted to act on the work when said holder is in loading position.
45. The combination, in mechanism of the class described, with a reciprocating ram, and a bracket carried by said ram, of a rod slidably arranged in said bracket, a carrier attached to said rod, and provided with converging guides, jaws slidably arranged on said guides, and yielding means normally to retain said jaws in their closest relative position.
46. The combination, in mechanism of the class described, with a reciprocating ram, and a bracket secured to said ram, of a carrier provided with converging guides, yielding means to support said carrier from said bracket, jaws slidably arranged on said guides, and yielding means normally to support said jaws in their closest relative position.
47. In a work holder, a rocker provided with holding means for work, and bearing members for said rocker, the latter having, between its axis and said work-holding means, means to receive waste matter resulting from the broaching operation on the work, and preventing the same from reaching said bearing members.
48. In a work holder, a shaft, and a rocker, provided with holding means for work, mounted on said shaft, and having, between its axis and said work-holding means, means to receive waste matter resulting from the broaching operation on the work, and prevent the same from reaching the bearing members of and for said rocker.
49. In a work holder, bearing members spaced apart, a shaft journaled in said members, and a rocker, provided with holding means for work, mounted on said shaft, and having, between its axis and said work-holding means, means to receive waste matter resulting from the broaching operation on the work, and prevent the same from reaching the contiguous surfaces between said rocker and said bearings.
50. In a work holder, a shaft, and a rocker, provided with holding means for work, mounted on said shaft, and having, on the sides and between the axis thereof and said work-holding means, troughs adapted to receive waste matter resulting from the broaching operation on the work, and to permit the same to pass away from said rocker, without fouling the bearing members of and for the rocker.
